CYCLIC METHOD FOR REMOVAL OF IMPURITIES FROM COKE OVEN TAR BY WATER WASHING

Austin N. Heller, Ramsey, N.J., and John H. Staub, Philadelphia, Pa., assignors to Allied Chemical Corporation, a corporation of New York

Application June 24, 1957, Serial No. 667,433

4 Claims. (Cl. 208—39)

This invention relates to an improved method for extracting water-soluble salts from water-immiscible liquids, and more particularly refers to a new and improved method of carrying out the removal of chlorides from heavy coke oven tar.

Coke oven tar is a vaporous product resulting from the destructive distillation of coal. In the refining of coke oven tar, the crude tar is initially condensed from coal gas and flushed from gas mains by recirculated NH_3 liquor. Crude condensed tar and NH_3 liquor pass to tar and liquor decanter tank, where solid sludge settles out. Tar and liquor go to a storage tank where tar flows under a weir to a tar overflow tank, thence to a tar storage tank. The semi-finished tar, also termed crude tar, invariably contains some liquor.

It is essential that wet tars be dried before the distillation step in refining for production of finished tars since the ammonium chloride in the aqueous liquor would otherwise plug up condenser tubes and cause severe corrosion to still bottoms. Also excessive moisture particularly in the form of slugs of water results in violent bumping during distillation, with resultant danger to operating personnel as well as poor heat economy and malperformance of the unit. Removal of excess aqueous liquor is therefore an essential preliminary to safe, controllable and economical tar refining.

Conventional methods of removing ammonium chloride from tar are based on long settling of the tar at elevated temperatures in an effort to cause settling out of chloride containing water, or on adding water in small amounts and separation of the aqueous phase by such means as centrifuging. These methods have proven costly and time consuming, and in the case of heavy tar having a specific gravity at 25/25° C. above 1.10, ineffective to reduce the chloride and water content to a satisfactorily low limit due to the presence of liquor occluded by the heavy coke oven tar as a water-in-oil emulsion. While it is important to reduce the chloride content of coke oven tar to below two pounds per 1,000 gallons of tar and of water to below 2% by volume of the coke oven tar in a rapid, economical and efficient method, in addition, it is important to accomplish this result without creating a pollution problem and with a minimum consumption of water, which is expensive and in certain locations a scarce commodity, and also to effect recovery of waste phenolics and ammonium chloride.

One object of the present invention is to provide an efficient, economical method of reducing the chloride content of the coke oven tar (measured as NH_4Cl) to below two pounds per 1,000 gallons of tar and the water content of the tar to below 2% by volume of the tar.

Another object of the present invention is to provide a method of reducing the chloride and water contents of coke oven tar to a low level of concentration employing a small amount of water for effecting same.

A further object of the present invention is to provide a method for reducing the ammonium chloride content and water content of coke oven tar to a low level of

2

concentration which avoids pollution with waste water and permits recovery of phenolics and ammonium chloride. Other objects and advantages will be apparent from the following description and accompanying drawing.

- 5 In accordance with the present invention, efficient, economical reduction of ammonium chloride to below two pounds per 1,000 gallons of tar and of water to below 2% by volume of tar, with concomitant production of an aqueous solution containing phenolics and ammonium chloride adapted for recovery of the phenolics and ammonium chloride, may be accomplished by contacting crude coke oven tar containing unseparated ammoniacal liquor, i.e. occluded aqueous liquor having dissolved therein ammonium chloride and phenolics, particularly heavy 10 crude coke oven tar of a specific gravity at 25/25° C. above 1.14 and a float test above 80 seconds at 32° F., with a mixture containing a major portion of recycled aqueous solution and a minor portion of make-up water in the proportion of 0.6—2.0, preferably 0.8—1.3, volumes 15 aqueous mixture to one volume of crude coke oven tar, effecting intimate contact between the coke oven tar and aqueous liquor, heating said mixture of tar and aqueous liquor to a temperature between 180° and 350° F., preferably 250—350° F., and under sufficient pressure to prevent substantial vaporization from the mixture, effecting separation of the mixture of heated coke oven tar and aqueous liquor into two phases by settling at a temperature within the range of 180—350° F., preferably 250—350° F., under sufficient pressure to prevent substantial 20 vaporization into an aqueous layer and a tar layer, preferably effecting said settling by flowing the mixture substantially horizontally through a substantially horizontally disposed settling section and thence into a vertical settling section, withdrawing the tar layer and subjecting 25 it to reduced pressure to effect flash vaporization of a small amount of volatile aqueous constituents contained therein, discharging the coke oven tar having a low level of concentration of ammonium chloride and water in an amount of less than two pounds ammonium chloride per 30 1,000 gallons tar and less than 2% water by volume of tar, condensing vapors evolved by said flash vaporization of the tar, preferably passing said vapors in indirect contact with crude coke oven feed tar to preheat said crude feed tar and to condense said vapors, returning said condensate for contact with incoming crude coke 35 oven tar, recirculating aqueous layer for further contact with crude heavy coke oven tar, preferably first passing the recirculated layer in indirect heat exchange with incoming crude coke oven tar, discharging a small amount, about 5—25%, preferably 10—20%, of the recirculating aqueous liquor, introducing about 5—25%, preferably 10—20%, make-up water by volume of recirculating liquor in admixture with the circulating aqueous liquor sufficient to maintain the amount of circulating liquor substantially constant.
- 40 The accompanying drawing is a diagrammatic flow sheet illustrating one method of practicing the present invention.
- 45 Referring to the drawing, crude or semi-finished tar produced by high temperature carbonization of coal having a specific gravity within the range of 1.1—1.30, particularly above 1.14 and a float test above 80 seconds at 32° F., containing from 5 to as much as 25 pounds ammonium chloride per 1,000 gallons of tar and from 4 to 50 20% by volume water, which latter has a phenolics, a mixture of phenol and homologues of phenol, content of 15,000 to 20,000 p.p.m., enters through line 1, flows through condenser 2 wherein it passes in indirect contact with flash vapors entering condenser 2 through line 3 and discharging through line 4 thereby condensing the flash vapors and transferring heat to the crude coke oven feed tar leaving condenser 2 through line 5. The preliminarily 55
- 60
- 65
- 70

heated coke oven feed tar is further preheated in heat exchanger 6 by indirect contact with hot recirculated liquor entering through line 7 and discharging through line 8. Preheated crude coke oven tar discharges from heat exchanger 6 through line 9 into crude tar storage tank 11 which, if desired, may be provided with heating means such as a steam coil, not shown in the drawing, to preheat the crude tar. Crude tar at a temperature of from 60 to about 200° F. is withdrawn from storage tank 11 through line 12 and directed by pump 13 through line 14, flow controller 15 and line 16 into mixing tank 17 provided with a high speed propeller-type mixer 18. Aqueous liquor flowing through line 19 and flow controller 21, or line 22 and flow controller 23, is admixed with the tar in mixing tank 17. Crude heavy coke oven tars are capable of holding water in excess of 12% of the weight of the tar in stable water-in-oil emulsions, and this kind of aqueous solution does not easily settle out to a sufficient degree to effect a high degree of removal of ammonium chloride from the tar. One of the factors important to achieve effective removal of ammonium chloride is contacting the tar in mixing tank 17 with 0.6-2.0, preferably 0.8-1.3, volumes aqueous liquor per volume of tar. This, coupled with intimate mixing, prepares the mixture of tar and aqueous liquor for separation of the aqueous phase from heavy tar to produce a tar of low ammonium chloride and low water content. The high speed propeller-type mixer effects intimate mixing of the tar and aqueous solution such that the ammonium chloride occluded within the tar is transferred to the aqueous solution. This transfer occurs when microscopic thin films of tar are formed in contact with the aqueous solution through shearing action accompanied by mechanical mixing. Flow controllers 15, 21 and 23 are set to maintain the volume of tar pumped to mixing tank 17 from tar storage tank 11 in the desired proportion of one volume tar to 0.6-2.0 volumes aqueous liquor entering mixer 17 through lines 19 or 22.

It is obvious that the lower the quantity of aqueous solution remaining occluded in the wash tar after recovery of a separate aqueous phase, the less will be the chloride content of the washed tar. It follows that reducing the amount of aqueous solution in the washed tar permits increasing the average ammonium chloride content of the recycled aqueous solution and thereby reduces the bleed stream of aqueous by-product. It therefore follows that effective separation of the contacted phases to achieve a minimal concentration of aqueous solution in the washed tar phase is an important step in the process.

Separation of the aqueous liquor may be accomplished by withdrawing the contents of mixing tank 17, subjected to agitation by high speed propeller-type mixer 18, through line 24 and thence by means of pump 25, raised to superatmospheric pressure and pumped via line 26, through flow controller 27 to tar heater 28 wherein the mixture is heated to a temperature of 180-350° F. Although the mixture of aqueous liquor and tar may be heated to a temperature of about 180-200° F. under atmospheric pressure, subsequent separation of such mixture under the conditions requires a long time, particularly for heavy tars having a specific gravity above 1.14. Consequently, it is desirable to heat the mixture to a temperature within a range of about 250-350° F. and under sufficient superatmospheric pressure, generally in excess of 50 p.s.i.g. and below 250 p.s.i.g., to prevent vaporization of the volatile constituents of the mixture and to effect separation under the conditions.

The heated mixture of tar and aqueous liquor discharges from tar heater 28 through line 29 and pressure regulator 31 into continuous settler 32. An economically sized settler, designed as illustrated by continuous settler 32, operating under superatmospheric pressure, is composed of a horizontal portion 33 and a vertical portion 34. The purpose of the horizontal portion is to effect preliminary settling of phases accompanied by slow forward flow, which flow prevents stratification of droplets of one

phase within the other phase, and aids the small droplets to coalesce and thereby more rapidly migrate out of the opposite phase. The vertical section of the continuous settler should have at least as large or larger cross-sectional area as the horizontal section in order to prevent turbulence occurring at the union of horizontal and vertical sections of the settler.

The tar phase settles out in the vertical portion 34 of continuous settler 32, passes through line 35, flow controller 36, pressure reducer 37 into flash drum 38 maintained at a lower pressure wherein further reduction of tar water content is accomplished by flash evaporation and the flash vapors released from the top of flash drum 38 through line 3. Product tar, substantially free of ammonium chloride and water, is withdrawn from the bottom of flash drum 38 through line 41 and sent through line 42 to storage. The use of flash dehydration by release of pressure is particularly advantageous in the treatment of heavy tars which resist complete separation of water from the tar in the settler. Further, the use of flash evaporation in conjunction with the continuous settler speeds up the operation and permits the use of smaller size settling equipment, in that complete separation of the water may not be accomplished in the settler but may be effected in flash drum 38 in a much more rapid and expeditious manner. For lighter tars wherein separation of the aqueous phase from the tar is quite complete and tar may be sent directly through lines 43 and 42 to storage, separation of the aqueous phase from the tar in settler 32 may be rapidly accomplished, in a matter of 10-60 minutes.

The aqueous phase passes up the vertical section 34 of continuous settler 32 via line 46, through flow controller 47, thence through line 7 where it is cooled by countercurrent contact with crude feed tar in heat exchanger 6 and then passes through pressure regulator 10 in line 8, thence through lines 48 and 49 to liquor decenter tank 51, or through lines 48 and 52 into alternate liquor decanter tank 53. In some instances the aqueous phase contains small amounts of crude tar, generally less than 1% suspended in the liquor. In these circumstances, the liquor is sent via lines 48, 49 and 52 to alternate liquor decanter tanks wherein settling of the small amount of tar in the liquor occurs. In this manner, a small amount of clarified liquor, about 5-25%, preferably 10-20% by volume of the recirculated liquor, may be withdrawn from tank 51 through line 54 and from tank 53 through line 55 and sent by pump 56 for recovery of ammonia and phenolics. Aqueous liquor, recirculating through line 48, requiring no additional clarification, may be sent directly to mixing tank 17 via lines 57 and 19 or only one liquor decanter tank need be employed. Also a small amount of recirculated liquor may be bled off from the stream flowing through line 48 and discharged through lines 58 and 54 for recovery of ammonia and phenolics. To compensate for the withdrawal of product liquor, make-up water is introduced into the circulating system through lines 59 and 61 joining the stream of recirculated liquor flowing through line 48, or through lines 62 and 63 into liquor decenter tank 51, or through lines 62 and 64 into liquor decanter tank 53. Thus by recycling aqueous liquor over and over again with only a small bleed off and the addition of a small amount of make-up water, there is accomplished reduction of the ammonium chloride content of the tar to a value below two pounds per 1,000 gallons tar and reduction of water content to below 2% by volume with consumption of only a small amount of make-up water and the production of a small amount of liquor which contains phenolics and ammonium chloride in sufficient concentration to permit recovery therefrom and eliminates a waste disposal and pollution problem. Liquor from tanks 51 and 53 is sent via lines 65 and 66 and line 67 by pump 68 through lines 69, 19 and flow controller 21 into mixing tank 17. Settled tar from the bottom of

tanks 51 or 53 is likewise pumped via lines 71, 72, 73 by pump 74 through line 22 and flow controller 23 into mixing tank 17.

The following examples illustrate the present invention.

Example 1

Sixteen thousand gallons of crude coke oven tar having a specific gravity at 15.5° C./15.5° C. of 1.248 and containing 8.5 pounds ammonium chloride per 1,000 gallons of tar and 5.8% water by volume of the tar was collected in a crude tar storage tank and processed in apparatus as illustrated in the drawing. Equal volumes of crude tar and aqueous liquor were intimately mixed in the mixing tank by means of a high speed propeller-type mixer. The aqueous liquor was composed of 83.65% recirculated liquor and 16.35% replacement water. The mixture of tar and aqueous liquor was heated to 304° F. and introduced into the continuous settler under superatmospheric pressure of 140 p.s.i.g. The residence time in the settler was 19.8 minutes. The aqueous layer was recirculated to the liquor decanter tank wherein, together with make-up water, the mixture was further contacted with additional crude coke oven tar. An amount of aqueous liquor, about equal to the amount of make-up water, was discharged from the system for recovery of phenolics and ammonia. The tar withdrawn from the continuous settler contained 0.73 pounds ammonium chloride per 1,000 gallons of tar and about 2% water. Passage of the tar to a flash drum further reduces the water content of the tar.

Example 2

Another batch of 16,000 gallons of crude coke oven tar was collected in the crude tar storage tank. This tar was a heavy tar similar to the heavy feed tar of Example 1 but having 14.2 pounds ammonium chloride per 1,000 gallons of tar and three volume percent water. The operation was similar to that of Example 1, differing principally in that the composition of the liquor was 86% recirculated liquor and 14% make-up water and the residence time in the continuous settler was 28.2 minutes. The coke oven tar product, after passing through the flash drum, contained 0.9 pounds ammonium chloride per 1,000 gallons tar and 2.0% water.

Although certain preferred embodiments of the invention have been disclosed for purpose of illustration, it will be evident that various changes and modifications may be made therein without departing from the scope and spirit of the invention.

We claim:

1. A process for the treatment of crude coke oven tar containing unseparated ammoniacal liquor, i.e. occluded aqueous liquor having dissolved therein ammonium chloride and phenolics, for reduction of ammonium chloride to below two pounds per 1,000 gallons of tar and of water to below 2% by volume of tar with concomitant production of an aqueous solution containing phenolics and ammonium chloride adapted for recovery of the phenolics and ammonium chloride which comprises continuously recirculating aqueous liquor in a closed circuit in which a mixture of the aqueous liquor with a minor proportion of make-up water is intimately contacted with crude coke oven tar in the proportion of 0.6-2.0 volumes aqueous mixture to one volume of crude coke oven tar, heating said mixture of tar and aqueous liquor to a temperature between 180° and 350° F. under sufficient pressure to prevent substantial vaporization from the mixture, effecting separation of the mixture of heated coke oven tar and aqueous liquor into two phases by settling at a temperature within the range of 180-350° F. under sufficient pressure to prevent substantial vaporization into an aqueous layer and a tar layer, withdrawing the tar layer and subjecting it to reduced pressure to effect flash vaporization of a small amount of volatile aqueous constituents contained therein, discharging the flashed coke

oven tar having a low concentration of ammonium chloride and water, recirculating aqueous layer as aqueous liquor for further contact with crude heavy coke oven tar, discharging a small amount, about 5-25%, of the recirculating aqueous liquor, and introducing about 5-25% make-up water by volume of circulating liquor in admixture with the circulating aqueous liquor sufficient to maintain the amount of circulating liquor substantially constant.

5 2. A process for the treatment of crude coke oven tar containing unseparated ammoniacal liquor, i.e. occluded aqueous liquor having dissolved therein ammonium chloride and phenolics, for reduction of ammonium chloride to below two pounds per 1,000 gallons of tar and of water to below 2% by volume of tar with concomitant production of an aqueous solution containing phenolics and ammonium chloride adapted for recovery of the phenolics and ammonium chloride which comprises continuously recirculating aqueous liquor in a closed circuit

10 in which a mixture of the aqueous liquor with a minor proportion of make-up water is intimately contacted with crude coke oven tar having a specific gravity at 25/25° C. above 1.14 and a float test above 80 seconds at 32° F. in the proportion of 0.8-1.3 volumes aqueous mixture to one volume of crude coke oven tar, heating said mixture of tar and aqueous liquor to a temperature between 250° and 350° F. under sufficient superatmospheric pressure to prevent substantial vaporization from the mixture, effecting separation of the mixture of heated coke oven tar and aqueous liquor into two phases by settling at a temperature within the range of 250-350° F. under sufficient super-atmospheric pressure to prevent substantial vaporization into an aqueous layer and a tar layer, withdrawing the tar layer and subjecting it to reduced pressure

15 to effect flash vaporization of a small amount of volatile aqueous constituents contained therein, discharging the flashed coke oven tar having a low concentration of ammonium chloride and water, recirculating aqueous layer as aqueous liquor for further contact with crude heavy coke oven tar, discharging a small amount, about 10-20%, of the recirculating aqueous liquor, and introducing about 10-20% make-up water by volume of circulating liquor in admixture with the circulating aqueous liquor sufficient to maintain the amount of circulating liquor substantially constant.

20 3. A process for the treatment of crude coke oven tar containing unseparated ammoniacal liquor, i.e. occluded aqueous liquor having dissolved therein ammonium chloride and phenolics, for reduction of ammonium chloride to below two pounds per 1,000 gallons of tar and of water to below 2% by volume of tar with concomitant production of an aqueous solution containing phenolics and ammonium chloride adapted for recovery of the phenolics and ammonium chloride which comprises continuously

25 recirculating aqueous liquor in a closed circuit in which a mixture of the aqueous liquor with a minor proportion of make-up water is intimately contacted with crude coke oven tar in the proportion of 0.6-2.0 volumes aqueous mixture to one volume of crude coke oven tar, heating said mixture of tar and aqueous liquor to a temperature between 180° and 350° F. under sufficient pressure to prevent substantial vaporization from the mixture, effecting separation of the mixture of heated coke oven tar and aqueous liquor into two phases by settling at a tem-

30 perature within the range of 180-350° F. under sufficient pressure to prevent substantial vaporization into an aqueous layer and a tar layer, withdrawing the tar layer and subjecting it to reduced pressure to effect flash vaporization of a small amount of volatile aqueous constituents

35 contained therein, discharging the flashed coke oven tar having a low concentration of ammonium chloride and water, condensing vapors evolved by said flashed vaporization of the tar, returning said condensate for contact with incoming crude coke oven tar, recirculating aqueous layer as aqueous liquor for further contact with crude

heavy coke oven tar, discharging a small amount, about 5-25%, of the recirculating aqueous liquor, and introducing about 5-25% make-up water by volume of circulating liquor in admixture with the circulating aqueous liquor sufficient to maintain the amount of circulating liquor substantially constant.

4. A process for the treatment of crude coke oven tar containing unseparated ammoniacal liquor, i.e. occluded aqueous liquor having dissolved therein ammonium chloride and phenolics, for reduction of ammonium chloride to below two pounds per 1,000 gallons of tar and of water to below 2% by volume of tar with concomitant production of an aqueous solution containing phenolics and ammonium chloride adapted for recovery of the phenolics and ammonium chloride which comprises continuously recirculating aqueous liquor in a closed circuit in which a mixture of the aqueous liquor with a minor proportion of make-up water is intimately contacted with crude coke oven tar having a specific gravity at 25/25° C. above 1.14 and a float test above 80 seconds at 32° F. in the proportion of 0.8-1.3 volumes aqueous mixture to one volume of crude coke oven tar, heating said mixture of tar and aqueous liquor to a temperature between 250° and 350° F. under sufficient superatmospheric pressure to prevent substantial vaporization from the mixture, effecting separation of the mixture of heated coke oven tar and aqueous liquor into two phases by flowing the mixture through a substantially horizontally disposed settling section and thence into a vertical settling section by settling at a temperature within the range of 250- 30

350° F. under sufficient superatmospheric pressure to prevent substantial vaporization into an aqueous layer and a tar layer, withdrawing the tar layer and subjecting it to reduced pressure to effect flash vaporization of a small amount of volatile aqueous constituents contained therein, discharging the flashed coke oven tar having a low concentration of ammonium chloride and water, passing vapors evolved by said flashed vaporization of the tar in indirect contact with crude coke oven feed tar to preheat said crude feed tar and to condense said vapors, returning said condensate for direct contact with incoming crude coke oven tar, passing aqueous layer in indirect heat exchange with incoming crude coke oven tar, recirculating said aqueous layer as aqueous liquor for further contact with crude heavy coke oven tar, discharging a small amount, about 10-20%, of the recirculating aqueous liquor, and introducing about 10-20% make-up water by volume of circulating liquor in admixture with the circulating aqueous liquor sufficient to maintain the amount of circulating liquor substantially constant.
